UNITED STATES PATENT OFFICE.

WALTER CLARK, OF LONDON, ENGLAND, ASSIGNOR TO CARIBONUM LIMITED, OF LEYTON, ENGLAND.

INKING DEVICE.

Application filed August 23, 1924. Serial No. 733,788.

To all whom it may concern:

Be it known that I, WALTER CLARK, a subject of the King of Great Britain, residing at 128 The Avenue, Highams Park, 5 Chingford, London, E. 4, England, have invented certain new and useful Improvements in Inking Devices, of which the following is a specification.

This invention relates to improvements in 10 apparatus for applying ink to the felt, or other ink-receiving layer of a pad, or material requiring to be filled or permeated with colour.

A common example of such an article requiring to be permeated is the felt layer usually provided beneath the textile covering of a stamp pad, and the invention will be described in reference thereto, though it should be understood that it is also applicable to other pads or the like requiring to be filled with colour.

The object of the invention is to enable the colour to be applied to the receiving layer conveniently and expeditiously, and without loss of the liquid colour, or ink, which is the valuable substance in such an operation.

The method of inking employed in carrying out the present invention is of the known type in which the ink is drawn into the receiving layer by providing a higher pressure on the supply side than on the opposite side of the layer, and this difference in pressure may be obtained either by the creation of a positive or negative pressure, that is to say, a pressure higher than the atmosphere in the one case, or a suction or negative pressure when applied to the said opposite side, in which case the higher pressure of the atmosphere on the supply side operates to force the ink into the material.

An apparatus for impregnating inking pads according to the present invention 45 comprises a supporting frame, a reservoir frame, and means for clamping the frames one over the other, each frame having an open centre, the opening of the frames being such that a pad is given marginal support by the supporting frame, and when the frames are superposed, a marginal clamping of the pad between the frames is obtained.

The ink is placed in the open centre of the reservoir frame, when a pad has been 50 clamped between the frames, and the ink

is forced through the pad until the latter is impregnated. Preferably, suction is utilized to draw the ink into the pad, the material of which may be felt, for example.

Conveniently, the frames may be hinged 60 together so that there is vertical play at the hinges, and the clamping pressure is applied independently of the hinges towards the front of the frames, whereby a level relative displacement between the frames is obtained.

The opening in the supporting frame may be virtually the nozzle of a suction apparatus, the opening being provided with wires forming a support for the centre part 70 of the pad, which prevents the pad being drawn into the said passage by the suction. In place of wires, a supporting grid may be employed, or even a perforated area of the supporting surface. In use, the central 75 opening is filled with a measured quantity of ink or colour, the suction applied to the underside, and owing to the pressure of the atmosphere, the ink is driven into the material.

A pad suitable for a stamp pad may be composed of two layers of felt with a sheet of blotting paper between them, and the edges of this pad should be tightly held by the reservoir frame so that besides affording some support to the pad, they remain clean so that the operator can finish the making of the pad in a cleanly manner. The suction should be stopped before the ink is drawn right through the pad.

When completed, and in its final form, it will be found that the surface of the pad is suitably inked all over.

The accompanying drawings illustrate a preferred form of the invention as applied to the filling of the ink containing layer of a stamp pad and the like:

Fig. 1 is a plan view of the apparatus, with the reservoir frame open; Fig. 2 is also a plan showing the reservoir frame closed; Fig. 3 is a side elevation showing the attachment of the suction passages, and Fig. 4 is a detail view to an enlarged scale showing in side elevation the construction of the hinged joint with vertical play.

Referring to the drawings, 1 is a base plate upon which is provided a surface 2 for the reception of the material to be inked, say, a pad formed of two layers of felt with a piece of blotting paper between

them, as shown at 3 in Fig. 3. The opening in the central portion of the surface is provided with cross wires, or bars, such as 4, for supporting the pad over the opening in the surface 2, connected to the suction passage 5 as shown, so that the material is prevented from being drawn into the pipe 5. Guide bars 6, 7, and 8 are placed on three sides of the supporting surface so as to locate the material in correct position, being preferably formed as angle pieces, of which the upstanding flanges enter recesses 9, 10, and 11 respectively of the reservoir frame 12; this frame is hinged by the spindle 13 of the base plate, and is provided with a handle 14 by which it may be raised and lowered on to the material 3. 16, 17 are hand levers pivoted about the pins 18, 19, on the further side of which pins they are provided respectively with the inclined surfaces 20, 21 (see Fig. 3) so arranged that as the handles 16, 17 are turned about their pivots, the inclined surfaces will press down the edges of the frame 12 so as to exert pressure on the compressible felt 3 to such an extent that when in position as shown in Fig. 1, ink or colour may be poured into the recess 15 of the frame 12, and upon application of the suction from the passage 5, this colour will be drawn into the felt 3.

In order to assist in the operation of the handles 16, 17, the reservoir frame 12 may be chamfered or bevelled, as indicated at 25, which assures an easy riding of the cams up on to the top of the said frame 12.

The permeation of the ink into the felt may be stopped or continued as may be desired at any point by controlling the suction in the passage 5 until the felt is inked to the extent desired, say by a valve 26.

For the support of the frame 12 while the felt is being put in place, a bracket 22 is formed so that the frame can be raised against it in its open position.

In order that the reservoir frame 12, when clamped to the base plate 1, shall securely clamp the material on all its edges, it is preferred to construct the hinge connection in the following manner. The base plate 1 is provided with eyes or bearings 23, and towards each side of the reservoir frame 12 is fixed a similar eye or bearing 24, these bearings being connected to the hinge pin 13, which is carried by the eyes 24. The bearings 23 for the hinge pin 13 are elongated vertically as indicated at 23^a (Fig. 4) so that after the frame has been rotated on to the base plate 1, it may be displaced vertically with the eyes 24 and the hinge pin 13 under the action of the cams of the handles 16 and 17.

By the use of this invention any colour may be applied. A change of colour may be quickly provided for, by putting a second frame in the hinge, or a single reservoir

frame may be readily cleansed by dipping it in a suitable cleansing liquid; inks of varying density may be applied quickly by varying the degree of suction, and in such case this may be obtained without waste, and with a minimum amount of time and trouble. 70

Although in the specification it is mentioned that three guides 6, 7, and 8 are used, it will be obvious that two guides, such as 75 7 and 8, or 6 and 7, would be suitable. It is found in practice that three are preferable.

I claim:—

1. In apparatus for impregnating inking pads, the combination with an open supporting frame, an open reservoir frame, a hinge connecting the said two frames, allowing a vertical play at the hinge, pivoted cam members on one frame co-acting with a surface on the other frame, whereby the 80 85 said frames are pressed together independently of the hinge, and means for applying suction to the opening of the supporting frame.

2. In apparatus for impregnating inking pads, the combination with an open supporting frame, an open reservoir frame having recesses therein for the reception of guide members, means for clamping the frames together so that a pad portion between them receives marginal support, guide members on the said supporting frame for the purpose of locating the pad to be inked, and means for applying suction to the opening of the supporting frame. 90 95 100

3. In apparatus for impregnating inking pads, the combination with an open supporting frame, an open reservoir frame having recesses therein for the reception of guide members, a hinge connecting the said two frames, allowing a vertical play at the hinge, pivoted cam members on one frame co-acting with a surface on the other frame, whereby the said frames are pressed together independently of the hinge, guide members on the said supporting frame for the purpose of locating the pad to be inked, and means for applying suction to the opening of the supporting frame. 105 110 115

4. In apparatus for impregnating inking pads, the combination with an open supporting frame, a grid covering the opening thereof, an open reservoir frame having recesses therein for the reception of guide members, means for clamping the frames together so that a pad portion between them receives marginal support therefrom and central support from the said grid, guide members on the supporting frame for the purpose of locating the pad to be inked, and means for applying suction to the opening of the supporting frame. 120 125 130

5. In apparatus for impregnating inking pads, the combination with an open supporting frame, a grid covering the opening

thereof, an open reservoir frame having recesses therein for the reception of guide members, a hinge connecting the said two frames, allowing a vertical play at the hinge, 5 pivoted cam members on one frame co-acting with a surface on the other frame, whereby the said frames are pressed together independently of the hinge, guide members on the said supporting frame for 10 the purpose of locating the pad to be inked, and means for applying suction to the opening of the supporting frame.

6. In apparatus for impregnating inking pads, the combination with an open supporting frame, a grid covering the opening thereof, an open reservoir frame having recesses therein for the reception of guide members, means for clamping the frames together so that a pad portion between them 15 receives marginal support therefrom and central support from the said grid, guide members on the supporting frame for the purpose of locating the pad to be inked, a suction mouthpiece shaped at its upper 20

end to suit the opening of the supporting frame, and at its lower end provided with a union end suitable for connection to a suction pipe, and means for controlling the suction therein. 25

7. In apparatus for impregnating inking pads, the combination of an open supporting frame, a grid covering the opening thereof, an open reservoir frame having recesses therein for the reception of guide members, a hinge connecting the said two frames, allowing a vertical play at the hinge, a lever with a cam shaped end pivoted on the supporting frame and adapted to ride over the reservoir frame, guide members on the said supporting frame for 30 the purpose of locating the pad to be inked, means for applying suction to the opening of the supporting frame, and a valve for controlling the suction. 35

In testimony whereof I affix my signature. 40

WALTER CLARK.
